FEEDING DEVICE

Filed June 2, 1925

3 Sheets-Sheet 3

UNITED STATES PATENT OFFICE.

CHARLES C. STEWART, OF DETROIT, MICHIGAN.

FEEDING DEVICE.

Application filed June 2, 1925. Serial No. 34,449.

To all whom it may concern:

Be it known that I, CHARLES C. STEWART, a citizen of the United States, residing at Detroit, in the county of Wayne and State of Michigan, have invented certain new and useful Improvements in Feeding Devices, of which the following is a specification, reference being had to the accompanying drawings.

10 This invention relates to feeding devices and has relation more particularly to a device of this general character especially designed and adapted for use in connection with fowls, and it is an object of the invention to provide a feeder of this kind adapted to broadcast the feed.

Another object of the invention is to provide a device of this general character operating by power driven means and wherein 20 such operation is under remote control.

An additional object of the invention is to provide a device of this general character with means for broadcasting feed together with a mechanism under centrifugal control 25 for regulating such broadcasting.

A further object of the invention is to provide a device of this general character embodying a mechanism whereby in addition to effecting a requisite delivery of feed also 30 operates to effect requisite delivery of a supply of drinking water.

Furthermore, it is an object of the invention to provide a device of this kind embodying a supply hopper for feed together with 35 means automatically operating to indicate when said supply is substantially exhausted.

The invention consists in the details of construction and in the combination and arrangement of the several parts of my improved feeding device whereby certain important advantages are attained and the device rendered simpler, less expensive and otherwise more convenient and advantageous for use, as will be hereinafter more fully set 45 forth.

The novel features of my invention will hereinafter be definitely claimed.

In order that my invention may be the better understood, I will now proceed to describe the same with reference to the accompanying drawings, wherein:—

Figure 1 is a view in side elevation with a portion broken away of a feeding device constructed in accordance with an embodiment 55 of my invention;

Figure 2 is a vertical sectional view taken through the structure as illustrated in Figure 1, with certain of the parts in elevation;

Figure 3 is a fragmentary view in top plan illustrating the centrifugal or governor controlled means as herein employed; 60

Figure 4 is an enlarged fragmentary view partly in section and partly in plan illustrating certain details of construction as illustrated in Figure 3; 65

Figure 5 is a sectional view taken substantially on the line 5—5 of Figure 4;

Figure 6 is a view in top plan and of somewhat a diagrammatic character illustrating the means directly associated with the doors 70 of the distributing members;

Figure 7 is a fragmentary view in bottom plan illustrating the slide valve as herein employed;

Figure 8 is a fragmentary view partly in 75 section and partly in plan of the valve for controlling the water feed.

As disclosed in the accompanying drawings, H denotes a casing or housing of requisite dimensions which is provided with the supporting legs 1 carrying the ground engaging wheels 2 whereby the device in its entirety may be readily transported from one location to another as desired. 80

The top 3 of the casing or housing is provided with an entrance opening 4 of requisite dimensions which is normally closed by the lid or cover 5, said opening 4 providing means whereby ready access may be had within the casing or housing H to the feed hopper F and the water tank T therein for the purpose of replenishing. 85

The hopper F is vertically disposed and is maintained in desired position by the posts or columns 6 certain of said columns being secured directly to the side members 7 comprised in a conveyor or elevating mechanism to be hereinafter referred to, while the other of said posts or columns being secured directly to the floor or bottom 8 of the casing or housing H. The hopper F is open at the top and tapers toward the bottom, the bottom wall 9 of which being provided with a discharge opening 10 normally closed by the slide valve 11. 95

Arranged within the hopper F and hingedly secured, as at 12, to a side wall thereof is a swinging contact member 14, the free end portion of which being normally urged outwardly by a spring 15 interposed 100

105

110

between said contact member and the adjacent wall of the hopper F.

When there is a supply of grain or kindred chicken feed within the hopper F, the 5 weight of such feed forces the contact member 14 toward the adjacent wall of the hopper F or into open position. As the feed passes out from the hopper F and the level thereof drops below the contact member 10 14 the spring 15 will urge said contact member 14 into requisite engagement with a stationary contact 17 and as said contacts 14 and 17 are interposed in an operating circuit 18 for a bell or other signal, such signal 15 will be caused to operate to give indication that the hopper F needs replenishing. The signal may be located within the dwelling or at any other location which is deemed preferable. 20 The lower end of the hopper F is continued by a box 19 from the inner side of which extends a conduit 20 of requisite cross sectional configuration and dimensions, said conduit 20 leading to the opposite 25 end portion of the casing or housing H and terminating in an outwardly and downwardly inclined chute 21 extending exteriorly of the casing or housing H. The lower marginal portions of the side walls 30 of the conduit 20 and of the box 19 are secured to the side members 7 of the elevator or conveying mechanism hereinbefore referred to. These members 7 are disposed on a desired upward incline in a direction 35 away from the box 19 and are supported in desired position by the posts or columns 22 suitably mounted upon the floor 8 of the casing or housing H. The bottom of the box 19 and the conduit 20 are in continuity 40 providing a unitary structure 23 over which traverses the upper stretch of the grain drag D, said drag being disposed over the rollers 24 rotatably supported by and between the members 7 adjacent the opposite 45 ends thereof, said drag serving to elevate or convey the feed dropped from the hopper F upwardly through the conduit 20 and discharge the same within the chute 21.

Rotatably supported by the lower portions 50 of the side members 7 and extending outwardly therebeyond is a shaft 25 one end portion of which being provided with the gear 26 meshing with a smaller gear 27 carried by the shaft 28 of the lower roller 24 whereby upon rotation of the gear 26 requisite travel will be imposed to the upper stretch of the drag D. As herein disclosed, the gear 26 is driven by the motor M of an electrical type. The operating circuit 29 for this motor M is adapted to extend within a dwelling or other desired location and is also adapted to have interposed therein a time controlled circuit maker and breaker so that at predetermined times and for a 60 desired period the drag D may be operated

to deliver feed to the chute 21. As the time controlled circuit maker and breaker in itself forms no part of the present invention it is believed that a detailed description and illustration thereof is unnecessary. 70

The lower or free end portion of the chute 21 is in communication with a fan casing 30 and the outlet spout 31 for said casing is in communication from below with an upstanding cylindrical member 32. 75 The extended portion of the chute 21 and the fan casing 30 are further supported by the brackets 33, said brackets also providing a mounting for the fan shaft 34 disposed through the casing 30 and upon which the fan 35 within the casing 30 is fixed. An extended portion of the shaft 34 is provided with a pulley 36 with which is operatively engaged the endless belt 37, said belt being also directed around a pulley 38 fixed to the shaft 25 hereinbefore referred to so that the fan 35 is caused to operate in unison with the shaft 25. 80

The forward wall of the cylindrical member 32 is open but normally closed by the outwardly swinging hinged doors 39 which, when in open position, permit the feed under the influence of the fan 35 to be broadcasted or scattered. 90

The doors 39 at the upper portions thereof and adjacent to their hinged connection with the member 32 are provided with the outstanding arms 40. Operatively engaged with one of the arms 40 is a rearwardly directed rod 41 also operatively engaged 100 with an end portion of an elongated lever 42. The opposite end portion of the lever 42 is pivotally connected, as at 43, with a rearwardly directed arm 44 carried by a table or shelf 45. This shelf 45 is carried 105 by the upper end portion of a post 46 mounted upon the upper wall of the chute 21 rearwardly of but in close proximity to the cylindrical member 32. The lever 42 at a point relatively close to its pivotal connection 43 has operatively engaged therewith an end portion of a forwardly directed link 47 the opposite end portion of said link being operatively engaged with the inner 110 end portion of a lever 48. This lever 48 substantially midway its ends is pivotally connected, as at 49 with the table or shelf 45. The outer end portion of this lever 48 has operatively engaged therewith an end portion of a second forwardly directed link 50 the opposite end portion of which being operatively engaged with a tail extension 51 of a lever 52. This lever 52 is pivotally connected, as at 53, with the table or shelf 45 and is disposed in a direction opposite 115 to that of the lever 42. The outer or free end portion of this lever 52 is operatively engaged by the rod 54 with the outstanding arm 40 carried by the second door 39. The operative connection between the levers 120 125 130

42 and 52 is such as to cause, upon swinging movement of the lever 48, the doors 39 to move in unison into either open or closed position.

5 The outer end portion of the lever 48 also has operatively connected therewith an extremity of an operating rod 55, said rod extending within the housing or casing H and having its inner end portion operatively connected, as at 56, with an end portion of a lever 57. The opposite end portion of the lever 57 is pivotally connected, as at 58, with an outstanding arm or bracket 59 carried by the adjacent side member 7 comprised in the elevator or conveyor structure. The outer end portion of the lever 57 also has operatively engaged therewith an extremity of a retractile member or coil spring 60 the opposite end portion being suitably secured to the side member 7 just referred to. The tension of this member or spring 60 is such as to normally exert sufficient pull upon the rod 55 to normally maintain the doors 39 in their closed positions.

10 25 The lever 57 substantially midway its ends is provided with an outstanding arm 61 rigid with respect thereto and the outer end portion of said arm 61 has operatively engaged therewith an end portion of a link 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 2. A feeding device comprising, in combination, a hollow member having an opening, a door for closing said opening, a supply hopper, means for forcibly discharging feed within the hollow member to be broadcasted through the opening when the door is in open position, means for carrying the feed from the hopper to said first named means, and means for maintaining the door in open position when the second named means is in operation. 55
3. A feeding device comprising, in combination, a hollow member having an opening, a door for closing said opening, a supply hopper, means for forcibly discharging feed within the hollow member to be broadcasted through the opening when the door is in open position, means for carrying the feed from the hopper to said first named means, 60 means for maintaining the door in open position when the second named means is in operation, a valve for normally closing the discharge from the hopper, and means operatively connected with the last named 65
- 20 means for moving said valve into open position when the second named means is in operation. 70
4. A feeding device comprising, in combination, a hollow member having an opening, a door for closing said opening, a supply hopper, means for forcibly discharging feed within the hollow member to be broadcasted through the opening when the door is in open position, means for carrying the feed from the hopper to said first named means, 75 means for maintaining the door in open position when the second named means is in operation, a pipe leading from a water supply, a normally closed valve interposed therein, and an operative connection between said valve and the last named means for maintaining said valve in open position 80 when the second named means is in operation. 85
- 45 5. A feeding device comprising, in combination, a hollow member having an opening, a door for closing said opening, a supply hopper, means for forcibly discharging feed within the hollow member to be broadcasted 90 through the opening when the door is in open position, a drive shaft, centrifugal means carried by the shaft, an operative connection between said centrifugal means and the door for maintaining the door in open position 95 upon rotation of the shaft, and means for rotating said shaft.

In testimony whereof I hereunto affix my signature.

CHARLES C. STEWART.
